UNITED STATES PATENT OFFICE.

CARLTON H. ALLEN, OF GLENS FALLS, NEW YORK, ASSIGNOR OF ONE-HALF TO GREAT NORTHERN PAPER COMPANY, OF MILLINOCKET, MAINE, A CORPORATION OF MAINE.

STRAINER FOR PULP DIGESTERS.

Application filed January 18, 1922. Serial No. 530,139.

To all whom it may concern:

Be it known that I, CARLTON H. ALLEN, a citizen of the United States, residing at Glens Falls, in the county of Warren and 5 State of New York, have invented certain new and useful Improvements in Strainers for Pulp Digesters, of which the following is a specification.

This invention relates to the so-called "digesting" apparatus used in the cooking of chemical pulp, and is especially concerned with the strainners used in such apparatus.

During the cooking of a charge of pulp in a digester, it is necessary occasionally to 10 open the discharge pipe that leads from the upper part of the digester in order to draw off some of the fluids and thereby relieve the excessive pressure created in the digester by the liberation of sulphur dioxid. A 15 strainer is usually located in the neck of the digester to prevent the chips and other solid material from being forced into the discharge pipe by the rush of fluids out of the digester. Such strainners are the cause 20 of a great deal of trouble due to their liability to become clogged or plugged with chips, and it is usually the custom, therefore, to connect live steam to the relief side of the strainer so that when the strainer 25 has become plugged steam can be forced through it to clear it. The fact that it is necessary to resort to such an expedient obviously interferes with the operation of drawing off fluids from the digester, and it 30 is impossible to use such a strainer with an automatic mechanism for relieving pressure in the digester. It is the chief object of the present invention, therefore, to devise a strainer which will not be open to these 35 objections.

The nature of the invention will be readily understood from the following description when read in connection with the accompanying drawings, and the novel features will be particularly pointed out in the 40 appended claims.

Referring now to the drawings, the single figure is a vertical cross sectional view of the upper end or neck of a digester showing 45 a strainer located therein, this strainer being constructed in accordance with the present invention. Some parts of the apparatus are shown in elevation.

In the construction shown, 2 designates the cast steel shell of the digester, 3 the

grout, and 4 the acid-proof lining, all constructed and arranged in the usual manner. Fitted into the neck of the digester is a collar 5 which preferably is made of some material adapted to resist the action of the acid used in the pulp cooking operation, such for instance, as bronze of a suitable composition. It will be seen that this collar has a cylindrical part that forms the inner wall of the neck of the digester, and a flange 6 that overlies the upper end of the grout. A discharge pipe 7 projects through the casing 2 and is threaded into the collar 5, as clearly shown.

The strainer provided by this invention is 70 located in the chamber in the interior of the collar 5. This strainer, as shown, comprises a hollow cylindrical screen 8 made of suitable sheet metal, such for instance, as lead, and perforated, as clearly shown in the 75 drawings, to permit the escape of liquids and gases therethrough. This screen is substantially smaller in diameter than the collar 5 so that an annular space is provided 80 between the outer wall of the screen and the inner wall of the collar. A ring 10 made of brass, or other suitable metal, is riveted to the lower end of the screen 8 and serves the double purpose of forming a flange to strengthen this end of the screen, and also 85 of substantially closing the lower end of the annular space between the screen and collar and preventing the entrance of chips and other solid materials into said space. The upper end of the screen has a collar or 90 flange member 12 of angular cross section riveted thereto, this collar resting on the member 6 and supporting the screen in the neck of the digester.

Inasmuch as the screen 8 is usually made 95 of lead, and consequently offers relatively little resistance to distortion, this member is provided with a series of studs 14 projecting from its peripheral surface, each stud preferably having a reduced shank 100 which is headed over or expanded in a hole formed in the screen. The chips and other solid materials can enter the screen freely through its lower open end and as they are pushed outwardly against the screen by the 105 pressure in the digester, the studs 14 bear against the inner wall of the collar 5 and support the screen, preventing distortion which otherwise would render the screen useless.

The open end of the digester is closed by a cover plate 15 having a suitable lining 16 and held in place by several swing bolts 17. A lead gasket 18 is placed between the cover and the collar 6 to seal the joint between these parts.

It will now be appreciated that when the relief valve in the pipe 7 is opened during the process of cooking a charge, the fluids 10 in the upper part of the digester will escape through the screen, into the annular space between the screen and the collar 5, and thence into the pipe 7. This construction provides a very large screening area, and 15 even if the chips and other solids in the digester are forced against the inner surface of the screen in a manner which would plug the ordinary screen, there is still sufficient straining area operative in the screen here 20 shown to allow the drawing off process to continue uninterruptedly. The chips and other solids therefore cannot plug this screen sufficiently to prevent its operation. The fact that the screen is open at both ends 25 makes it unnecessary to remove this device after it has once been placed in position, the filling or charging operation being performed by dumping the materials into the digester just as though the screen were not 30 present.

Having thus described my invention, what I desire to claim as new is:

1. A strainer for pulp digesters and the like comprising a hollow sheet metal body 35 perforated to form a screen, and a series of supporting studs projecting from the periphery of said screen.

2. A strainer for pulp digesters and the like comprising a hollow sheet metal body

perforated to form a screen, a series of supporting studs projecting from the periphery of said screen, and a supporting flange at one end of said screen. 40

3. A strainer for pulp digesters and the like comprising a hollow sheet metal body 45 perforated to form a screen, a series of supporting studs projecting from the periphery of said screen, and a peripheral flange projecting laterally from each end of said screen. 50

4. In a digester, the combination of an annular screen open at both ends and having a peripheral flange at its upper end supporting the screen in the neck of the digester but spaced from the inner wall of said neck, 55 said screen having a series of studs projecting from the periphery thereof, a discharge pipe communicating with the space between said screen and said wall, a removable cover for closing the neck of the digester, and a peripheral flange at the inner end of said screen substantially preventing the entrance 60 of solids into said space. 65

5. In a digester having a reduced neck, the combination of an annular screen open 70 at its top and bottom and having a peripheral flange at its upper end resting on the upper end of said neck and removably supporting the screen in said neck but spaced from the inner wall of said neck, a peripheral flange at the lower end of said screen substantially closing the space between the wall of said neck and the screen, 75 a removable cover for closing the neck of said digester, and a discharge pipe communicating with the space between said screen and said wall. 80

CARLTON H. ALLEN.
